(57) CLAIM

The ornamental design for a headpiece as shown and described.

DESCRIPTION

FIG. 1 is a perspective view of a first embodiment of the headpiece;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a perspective view of a second embodiment of the headpiece;

FIG. 8 is a front elevational view thereof;

FIG. 9 is a rear elevational view thereof;

FIG. 10 is a left side elevational view thereof;

FIG. 11 is a right side elevational view thereof; and,

FIG. 12 is a top plan view thereof.

The broken line outline of the partial human figure in FIGS. 1 and 7 assists in illustrating how the headpiece may appear when in a position of use, but forms no part of the claimed design. The broken lines and unshaded surfaces within the bounds of the broken lines of the headpiece define portions of the headpiece that form no part of the claimed design.
